Charles L. Sebring INVENTOR.

UNITED STATES PATENT OFFICE.

CHARLES L. SEBRING, OF SEBRING, OHIO, ASSIGNOR TO THE SEBRING POTTERY COMPANY, OF SEBRING, OHIO.

DESIGN FOR AN ARTICLE OF MANUFACTURE.

49,464.

Specification for Design.

Patented July 25, 1916.

Application filed May 29, 1916. Serial No. 100,695. Term of patent 3½ years.

To all whom it may concern:

Be it known that I, CHARLES L. SEBRING, a citizen of the United States, residing at Sebring, in the county of Mahoning, State of Ohio, have invented a new, original, and ornamental Design for an Article of Manufacture, of which the following is a specification, reference being had to the accompanying drawing, forming a part thereof.

The figure is a plan view of my new de-

sign to be applied to an article of manufacture, a portion of the article only being shown.

I claim—

The ornamental design for an article of manufacture as shown.

CHARLES L. SEBRING.
